UNITED STATES PATENT OFFICE.

LUTHER V. MOULTON AND HOMER L. BOYLE, OF GRAND RAPIDS, MICHIGAN,
ASSIGNORS TO CHARLES E. WESTLAKE, OF SAME PLACE.

VENDING APPARATUS FOR LIQUIDS.

SPECIFICATION forming part of Letters Patent No. 424,428, dated March 25, 1890.

Application filed November 11, 1889. Serial No. 329,943. (No model.)

To all whom it may concern:

Be it known that we, LUTHER V. MOULTON and HOMER L. BOYLE, citizens of the United States, residing at Grand Rapids, in the county 5 of Kent and State of Michigan, have invented certain new and useful Improvements in Vending Apparatus for Liquids; and we do hereby declare the following to be a full, clear, and exact description of the invention, such as 10 will enable others skilled in the art to which it appertains to make and use the same.

Our invention relates to vending apparatus for liquids; and the object of our invention is to produce a simple durable device having a 15 suitable tank for containing the liquid to be vended and provided with mechanism whereby a measure of the liquid can be drawn from the tank by introducing a coin through a suitable opening into the mechanism of the apparatus, and that cannot be operated except by the introduction of such coin or some 20 equivalent article of substantially the same size, weight, and form; and the invention consists in the peculiar construction, combination, and arrangement of the various parts, as 25 hereinafter more fully described, and pointed out in the claims, reference being had to the accompanying drawings, wherein—

Figure 1 is a front elevation of a device embodying our invention; Fig. 2, a vertical section on the line xx of Fig. 1, and Fig. 3 a horizontal section on the line yy of Fig. 2.

Like letters and figures of reference indicate like parts in each of the several figures.

35 A represents any suitable tank for containing the liquid to be vended, and is provided with a false bottom C, and may also be provided with an inner receptacle B for containing ice to cool said liquid.

40 D is a case inclosing the vending mechanism, having a chamber between the false bottom 7 and the diaphragm 6 to protect said mechanism from injury.

E is a coin-chute consisting of a serpentine 45 tube communicating with a slot E' and provided with vent-openings W to prevent the device from being operated by air blown into the slot E'.

F is a measure which rests and is adjusted 50 to fit closely upon the platform G and has a closed bottom provided with a single opening

or port H'', which registers with a corresponding port or opening H in the platform G for admitting the liquid to the measure, and another port H' for discharging its contents into 55 the vessel J by means of spout I communicating with port H', and has a heavy cover 3 to hold it upon its seat on the platform when the tank is filled with a liquid, and vent-pipes 1 and 2 (2 being flexible for permitting a longitudinal movement of F) for permitting the 60 escape of air.

K is a pull-rod, which passes through the casing D, and is provided with a knob 3 and a spring S, having an adjusting-nut 5, and a 65 tight gland M, having a suitable packing to prevent the liquid from following the rod out of the tank. The rod K is attached to F by a loose joint L, and has a notch 4, into which takes the pawl N of the lever O, which is pivoted to the post R, resting upon false bottom 7. One end of the lever O is flattened and adapted to close the bottom of the coin-chute E. The other end passes through the loop-stop Q, (which is secured to and moves with 75 the rod K,) and is provided with adjustable weight P. In the chamber underneath the false bottom of D is arranged a cash-box U, which communicates with the coin-chute E by the opening T through the false bottom 7. 80

V is a drip-pipe communicating with the floor of the chamber containing the vessel J.

The apparatus operates substantially as follows: Liquid placed in the tank flows through the port H into the measure F, the 85 air escaping through the pipes 1 and 2. A coin introduced through the slot E', passing down the slot E, lodges upon the outer end of the lever O, depressing it sufficiently to disengage the pawl N from the notch 4; but 90 the opposite end of the lever is engaged at the same time by the loop-stop Q and prevents it from being depressed low enough to permit the coin to fall off the outer end until the rod K is drawn out. When this is done, 95 the stop Q, moving with the rod, permits the weighted end of the lever to rise, and the other end being at the same time depressed by the weight of the coin, the coin is disengaged from the sides of the chute and falls off 100 through the opening T into the cash-box U. At the same time the measure F is drawn

forward, closing the port H and opening the port H', permitting the contents of the measure to escape through the spout I, as already explained. The rod K being released, the 5 spring S causes it to resume its former position, pushing the measure F along upon its seat upon the platform until the ports H and H" again register. The weight P causes the lever O to resume its former position, the 10 pawl N re-engages the notch 4, the measure refills, and the operation may be repeated indefinitely.

Having thus described our invention, what we claim, and desire to secure by Letters Patent of the United States, is—

15 1. In a vending apparatus for liquids, the combination, with a suitable tank, of a platform arranged inside of said tank adapted to support a measure, said platform having a 20 port communicating with the interior of said tank, and another port communicating with a discharge-pipe, a measure resting on said platform and adapted to slide thereon, said measure having a closed top, and a bottom 25 having a port adapted to communicate alternately with said platform-ports, a vent-pipe on said measure for permitting the escape of air, and a rod for sliding said measure, arranged substantially as described, and for the 30 purposes set forth.

2. In a vending apparatus for liquids, the combination, with a suitable tank provided with a false bottom, of a platform supported upon said bottom and provided with a port 35 communicating with the interior of said tank, and another port communicating with a discharge-pipe, a measure resting on said platform and adapted to slide thereon, said measure having a closed top, and a bottom having 40 a port adapted to register alternately with the ports in said platform, and a flexible vent-pipe for permitting the escape of air.

3. In a vending apparatus for liquids, the combination, with a suitable tank for containing the liquids and a casing for inclosing the operating mechanism, of a coin-chute arranged within and communicating with the exterior of said casing, a pivoted lever having an arm adapted to close the bottom of 45 said coin-chute and provided with a weight at its other end, and a pawl arranged near the pivot, a pull-rod having a notch adapted to engage said pawl, and a measure arranged within said tank, said measure being adapted 50 to slide horizontally connected to said pull-rod, arranged substantially as described, and for the purposes set forth.

4. In vending apparatus for liquids, the combination, with a suitable tank for containing the liquid, of a coin-chute connected to said tank, a pivoted lever having a flattened surface at one end adapted to close the bottom of the chute and provided with an adjustable weight at the other end, and a pawl 65 arranged near the middle, a pull-rod provided with a notch adapted to engage with

7c said pawl, a stop secured to said rod and adapted to engage the weighted end of said lever, and a horizontally-movable measure attached to said pull-rod, arranged substantially as described, and for the purposes herein set forth.

5. In vending apparatus for liquids, in combination with a suitable tank and a casing attached to the tank, a curved coin-chute secured in the casing, a cash-box communicating with said coin-chute and arranged within said casing, a false bottom in said casing, a post attached to said false bottom, a lever pivoted to said post provided with a pawl 80 and having an arm provided with an adjustable weight, and another arm adapted to close the bottom of said coin-chute, a pull-rod having a notch adapted to engage said pawl and provided with a retracting-spring and having 85 an adjusting-nut, a loop-stop secured to said pull-rod adapted to engage with the weighted end of said lever, a gland, as M, surrounding said pull-rod, and a horizontally-movable measure attached to said rod, substantially as 90 described, and for the purposes set forth.

6. In vending apparatus for liquids, in combination with a suitable tank having a false bottom, a platform resting on said bottom having a port communicating with the interior of 95 said tank, and another port communicating with the discharge-pipe, a measure having a closed top and a bottom provided with a port adapted to communicate alternately with each 100 of said ports, said measure resting on said platform and adapted to slide horizontally thereon, a vent-pipe having a flexible portion and communicating with said measure and with the top of the tank, a pull-rod flexibly attached to said measure, a pivoted lever having a pawl adapted to engage said pull-rod and having an arm provided with an adjustable weight, and another arm adapted to receive a coin, a coin-chute adapted to conduct the coin onto said coin-supporting arm, a stop 110 secured to said pull-rod adapted to engage said weighted arm, and an adjustable retracting-spring for said pull-rod arranged substantially as described, and for the purposes set forth.

7. In vending apparatus, in combination with a suitable tank or vessel for containing the substance to be vended, and a suitable casing for the vending mechanism, a pull-rod having an end projecting from said casing adapted for operating the mechanism provided with a retracting-spring, a coin-chute communicating with the interior and exterior of said casing, a pivoted lever having a pawl adapted to engage with said pull-rod and having an arm adapted to close the bottom of the coin-chute, and an oppositely-projecting arm provided with an adjustable weight, a stop secured to and moving with said rod and adapted to engage said weighted arm when the opposite end of said lever is depressed, and mechanism for discharging a portion of 115 120 125 130

the substance to be vended attached to and operated by said pull-rod, substantially as described.

8. The combination, with a suitable tank or vessel for containing the substance to be vended, of a vertically-arranged curved and inclined coin-chute provided with openings in its sides, as W, a pivoted lever having an arm adapted to close the bottom of the coin-chute, and an oppositely-projecting arm provided with an adjustable weight, a pawl arranged near the said pivotal point of said lever, a pull-rod having a notch adapted to engage with said pawl and provided with a suitable 15 retracting-spring, as S, a stop, as Q, secured to

and moving with said pull-rod and adapted to engage with the weighted end of said lever when the opposite end is sufficiently depressed, and mechanism for discharging a portion of the substance to be vended arranged within the said vessel for containing the substance and attached to the inner end of said pull-rod, substantially as described.

In testimony whereof we affix our signatures in presence of two witnesses.
